6 SHEETS—SHEET 1.

<img alt="Technical cross-sectional diagram of a mechanical device, likely a pump or compressor, showing various components and their connections. The diagram includes labels such as 1, 2, 3, 4, 5, 6, 7, 8, 9, 10, 11, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 299, 300, 301, 302, 303, 304, 305, 306, 307, 308, 309, 309, 310, 311, 312, 313, 314, 315, 316, 317, 318, 319, 319, 320, 321, 322, 323, 324, 325, 326, 327, 328, 329, 329, 330, 331, 332, 333, 334, 335, 336, 337, 338, 339, 339, 340, 341, 342, 343, 344, 345, 346, 347, 348, 349, 349, 350, 351, 352, 353, 354, 355, 356, 357, 358, 359, 359, 360, 361, 362, 363, 364, 365, 366, 367, 368, 369, 369, 370, 371, 372, 373, 374, 375, 376, 377, 378, 379, 379, 380, 381, 382, 383, 384, 385, 386, 387, 388, 389, 389, 390, 391, 392, 393, 394, 395, 396, 397, 398, 399, 399, 400, 401, 402, 403, 404, 405, 406, 407, 408, 409, 409, 410, 411, 412, 413, 414, 415, 416, 417, 418, 419, 419, 420, 421, 422, 423, 424, 425, 426, 427, 428, 429, 429, 430, 431, 432, 433, 434, 435, 436, 437, 438, 439, 439, 440, 441, 442, 443, 444, 445, 446, 447, 448, 449, 449, 450, 451, 452, 453, 454, 455, 456, 457, 458, 459, 459, 460, 461, 462, 463, 464, 465, 466, 467, 468, 469, 469, 470, 471, 472, 473, 474, 475, 476, 477, 478, 479, 479, 480, 481, 482, 483, 484, 485, 486, 487, 488, 489, 489, 490, 491, 492, 493, 494, 495, 496, 497, 498, 499, 499, 500, 501, 502, 503, 504, 505, 506, 507, 508, 509, 509, 510, 511, 512, 513, 514, 515, 516, 517, 518, 519, 519, 520, 521, 522, 523, 524, 525, 526, 527, 528, 529, 529, 530, 531, 532, 533, 534, 535, 536, 537, 538, 539, 539, 540, 541, 542, 543, 544, 545, 546, 547, 548, 549, 549, 550, 551, 552, 553, 554, 555, 556, 557, 558, 559, 559, 560, 561, 562, 563, 564, 565, 566, 567, 568, 569, 569, 570, 571, 572, 573, 574, 575, 576, 577, 578, 579, 579, 580, 581, 582, 583, 584, 585, 586, 587, 588, 589, 589, 590, 591, 592, 593, 594, 595, 596, 597, 598, 599, 599, 600, 601, 602, 603, 604, 605, 606, 607, 608, 609, 609, 610, 611, 612, 613, 614, 615, 616, 617, 618, 619, 619, 620, 621, 622, 623, 624, 625, 626, 627, 628, 629, 629, 630, 631, 632, 633, 634, 635, 636, 637, 638, 639, 639, 640, 641, 642, 643, 644, 645, 646, 647, 648, 649, 649, 650, 651, 652, 653, 654, 655, 656, 657, 658, 659, 659, 660, 661, 662, 663, 664, 665, 666, 667, 668, 669, 669, 670, 671, 672, 673, 674, 675, 676, 677, 678, 679, 679, 680, 681, 682, 683, 684, 685, 686, 687, 688, 689, 689, 690, 691, 692, 693, 694, 695, 696, 697, 698, 699, 699, 700, 701, 702, 703, 704, 705, 706, 707, 708, 709, 709, 710, 711, 712, 713, 714, 715, 716, 717, 718, 719, 719, 720, 721, 722, 723, 724, 725, 726, 727, 728, 729, 729, 730, 731, 732, 733, 734, 735, 736, 737, 738, 739, 739, 740, 741, 742, 743, 744, 745, 746, 747, 748, 749, 749, 750, 751, 752, 753, 754, 755, 756, 757, 758, 759, 759, 760, 761, 762, 763, 764, 765, 766, 767, 768, 769, 769, 770, 771, 772, 773, 774, 775, 776, 777, 778, 779, 779, 780, 781, 782, 783, 784, 785, 786, 787, 788, 789, 789, 790, 791, 792, 793, 794, 795, 796, 797, 798, 799, 799, 800, 801, 802, 803, 804, 805, 806, 807, 808, 809, 809, 810, 811, 812, 813, 814, 815, 816, 817, 818, 819, 819, 820, 821, 822, 823, 824, 825, 826, 827, 828, 829, 829, 830, 831, 832, 833, 834, 835, 836, 837, 838, 839, 839, 840, 841, 842, 843, 844, 845, 846, 847, 848, 849, 849, 850, 851, 852, 853, 854, 855, 856, 857, 858, 859, 859, 860, 861, 862, 863, 864, 865, 866, 867, 868, 869, 869, 870, 871, 872, 873, 874, 875, 876, 877, 878, 879, 879, 880, 881, 882, 883, 884, 885, 886, 887, 888, 889, 889, 890, 891, 892, 893, 894, 895, 896, 897, 898, 899, 899, 900, 901, 902, 903, 904, 905, 906, 907, 908, 909, 909, 910, 911, 912, 913, 914, 915, 916, 917, 918, 919, 919, 920, 921, 922, 923, 924, 925, 926, 927, 928, 929, 929, 930, 931, 932, 933, 934, 935, 936, 937, 938, 939, 939, 940, 941, 942, 943, 944, 945, 946, 947, 948, 949, 949, 950, 951, 952, 953, 954, 955, 956, 957, 958, 959, 959, 960, 961, 962, 963, 964, 965, 966, 967, 968, 969, 969, 970, 971, 972, 973, 974, 975, 976, 977, 978, 979, 979, 980, 981, 982, 983, 984, 985, 986, 987, 988, 989, 989, 990, 991, 992, 993, 994, 995, 996, 997, 998, 999, 999, 1000, 1001, 1002, 1003, 1004, 1005, 1006, 1007, 1008, 1009, 1009, 1010, 1011, 1012, 1013, 1014, 1015, 1016, 1017, 1018, 1019, 1019, 1020, 1021, 1022, 1023, 1024, 1025, 1026, 1027, 1028, 1029, 1029, 1030, 1031, 1032, 1033, 1034, 1035, 1036, 1037, 1038, 1039, 1039, 1040, 1041, 1042, 1043, 1044, 1045, 1046, 1047, 1048, 1049, 1049, 1050, 1051, 1052, 1053, 1054, 1055, 1056, 1057, 1058, 1059, 1059, 1060, 1061, 1062, 1063, 1064, 1065, 1066, 1067, 1068, 1069, 1069, 1070, 1071, 1072, 1073, 1074, 1075, 1076, 1077, 1078, 1079, 1079, 1080, 1081, 1082, 1083, 1084, 1085, 1086, 1087, 1088, 1089, 1089, 1090, 1091, 1092, 1093, 1094, 1095, 1096, 1097, 1098, 1099, 1099, 1100, 1101, 1102, 1103, 1104, 1105, 1106, 1107, 1108, 1109, 1109, 1110, 1111, 1112, 1113, 1114, 1115, 1116, 1117, 1118, 1119, 1119, 1120, 1121, 1122, 1123, 1124, 1125, 1126, 1127, 1128, 1129, 1129, 1130, 1131, 1132, 1133, 1134, 1135, 1136, 1137, 1138, 1139, 1139, 1140, 1141, 1142, 1143, 1144, 1145, 1146, 1147, 1148, 1149, 1149, 1150, 1151, 1152, 1153, 1154, 1155, 1156, 1157, 1158, 1159, 1159, 1160, 1161, 1162, 1163, 1164, 1165, 1166, 1167, 1168, 1169, 1169, 1170, 1171, 1172, 1173, 1174, 1175, 1176, 1177, 1178, 1179, 1179, 1180, 1181, 1182, 1183, 1184, 1185, 1186, 1187, 1188, 1189, 1189, 1190, 1191, 1192, 1193, 1194, 1195, 1196, 1197, 1198, 1199, 1199, 1200, 1201, 1202, 1203, 1204, 1205, 1206, 1207, 1208, 1209, 1209, 1210, 1211, 1212, 1213, 1214, 1215, 1216, 1217, 1218, 1219, 1219, 1220, 1221, 1222, 1223, 1224, 1225, 1226, 1227, 1228, 1229, 1229, 1230, 1231, 1232, 1233, 1234, 1235, 1236, 1237, 1238, 1239, 1239, 1240, 1241, 1242, 1243, 1244, 1245, 1246, 1247, 1248, 1249, 1249, 1250, 1251, 1252, 1253, 1254, 1255, 1256, 1257, 1258, 1259, 1259, 1260, 1261, 1262, 1263, 1264, 1265, 1266, 1267, 1268, 1269, 1269, 1270, 1271, 1272, 1273, 1274, 1275, 1276, 1277, 1278, 1279, 1279, 1280, 1281, 1282, 1283, 1284, 1285, 1286, 1287, 1288, 1289, 1289, 1290, 1291, 1292, 1293, 1294, 1295, 1296, 1297, 1298, 1299, 1299, 1300, 1301, 1302, 1303, 1304, 1305, 1306, 1307, 1308, 1309, 1309, 1310, 1311, 1312, 1313, 1314, 1315, 1316, 1317, 1318, 1319, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1379, 1379, 1380, 1381, 1382, 1383, 1384, 1385, 1386, 1387, 1388, 1389, 1389, 1390, 1391, 1392, 1393, 1394, 1395, 1396, 1397, 1398, 1399, 1399, 1400, 1401, 1402, 1403, 1404, 1405, 1406, 1407, 1408, 1409, 1409, 1410, 1411, 1412, 1413, 1414, 1415, 1416, 1417, 1418, 1419, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1518, 1519, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1618, 1619, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1699, 1699, 1700, 1701, 1702, 1703, 1704, 1705, 1706, 1707, 1708, 1709, 1709, 1710, 1711, 1712, 1713, 1714, 1715, 1716, 1717, 1718, 1719, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1798, 1799, 1799, 1800, 1801, 1802, 1803, 1804, 1805, 1806, 1807, 1808, 1809, 1809, 1810, 1811, 1812, 1813, 1814, 1815, 1816, 1817, 1818, 1819, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, 1870, 1871, 1872, 1873, 1874, 1875, 1876, 1877, 1878, 1879, 1879, 1880, 1881, 1882, 1883, 1884, 1885, 1886, 1887, 1888, 1889, 1889, 1890, 1891, 1892, 1893, 1894, 1895, 1896, 1897, 1898, 1899, 1899, 1900, 1901, 1902, 1903, 1904, 1905, 1906, 1907, 1908, 1909, 1909, 1910, 1911, 1912, 1913, 1914, 1915, 1916, 1917, 1918, 1919, 1919, 1920, 1921, 1922, 1923, 1924, 1925, 1926, 1927, 1928, 1929, 1929, 1930, 1931, 1932, 1933, 1934, 1935, 1936, 1937, 1938, 1939, 1939, 1940, 1941, 1942, 1943, 1944, 1945, 1946, 1947, 1948, 1949, 1949, 1950, 1951, 1952, 1953, 1954, 1955, 1956, 1957, 1958, 1959, 1959, 1960, 1961, 1962, 1963, 1964, 1965, 1966, 1967, 1968, 1969, 1969, 1970, 1971, 1972, 1973, 1974, 1975, 1976, 1977, 1978, 1979, 1979, 1980, 1981, 1982, 1983, 1984, 1985, 1986, 1987, 1988, 1989, 1989, 1990, 1991, 1992, 1993, 1994, 1995, 1996, 1997, 1998, 1999, 1999, 2000, 2001, 2002, 2003, 2004, 2005, 2006, 2007, 2008, UNITED STATES PATENT OFFICE.

WILLIAM W. BIRNSTOCK, OF YORK, PENNSYLVANIA, ASSIGNOR TO YORK MILK MACHINERY COMPANY, OF YORK, PENNSYLVANIA, A CORPORATION OF PENNSYLVANIA.

BOTTLE-WASHING MACHINE.

Application filed July 15, 1921. Serial No. 484,875.

To all whom it may concern:

Be it known that I, WILLIAM W. BIRNSTOCK, a citizen of the United States, residing at York, in the county of York and 5 State of Pennsylvania, have invented new and useful Improvements in Bottle-Washing Machines, of which the following is a specification.

The present invention relates to machines 10 for handling or treating bottles in crates, and more particularly to machines for washing, rinsing and sterilizing milk bottles. The primary object of the invention is to provide a novel and improved machine of 15 this kind, whereby certainty in the functioning of its operative mechanisms is insured and durability is attained. The invention provides an improved mechanism for feeding or advancing the bottle-containing crates. 20 step-by-step, to the different operative mechanisms and through the machine, whereby reliability in the correct functioning of the machine, with respect to the bottles in the crates, is attained, and it also 25 provides novel and improved means for controlling and timing the operation of the operative mechanisms of the machine in correct relation with the operations of the bottle or crate-advancing mechanism.

30 To these and other ends, the invention consists in certain improvements and combinations and arrangements of parts, all as will be hereinafter more fully described, the features of novelty being pointed out particularly in the claims at the end of the specification.

In the accompanying drawings:

Figure 1 is a side elevation of a bottle washing, rinsing and sterilizing machine 40 constructed in accordance with the preferred embodiment of the invention;

Figures 2 and 2^a represent a horizontal section on an enlarged scale and taken on the line 2—2 of Figure 1;

45 Figure 3 represents a cross section through the machine taken on the line 3—3 of Figure 2^a and looking in the direction of the arrows;

Figure 4 represents a vertical section taken 50 longitudinally through the machine with the central portion of the machine broken away;

Figure 5 is a top plan view of one of the crate-feeding bars or members, showing the means for shifting the crate-engaging dogs from the inoperative dotted line position to 55 the operative full line position;

Figure 6 is a view similar to Figure 5 showing the means for shifting the dogs from the operative dotted line position to the inoperative full line position; and 60

Figure 7 is a detail sectional view, on an enlarged scale, taken through one of the crate-feeding bars, one of the crate-engaging dogs thereon and the adjacent co-operating parts. 65

Similar parts are designated by the same reference characters in the several views.

The present invention is applicable, in whole or in part, to machines of different kinds, wherein it is desirable or necessary to 70 handle or treat crates of bottles, or similar articles, automatically. The invention is particularly applicable to machines for washing and cleaning milk bottles while contained in crates, and the invention is 75 shown applied to a machine of this kind in the accompanying drawings and will be hereinafter described in detail. It is to be understood, however, that the invention is not restricted to the precise construction 80 shown, as equivalent constructions are contemplated and these will be included within the scope of the claims.

In the present instance, the machine comprises a body or base 1 which supports or 85 contains the different mechanisms of the machine and which is divided, by a suitable number of transverse partitions, into compartments, to contain the washing solution, the rinsing water and to collect the drip 90 from the bottles. In the present instance, the machine is of the type wherein the bottles are placed in inverted position in crates or racks having grid-like bottoms and during their passage through the machine, the as washing, rinsing, sterilizing and other treating fluids are projected upwardly into the inverted bottles, the drip from the bottles being collected in the different compartments. As shown, a compartment 2 is provided to 100 contain a suitable washing solution, and a pair of headers 3 is located above this com-

partment and provided with nozzles which are directed upwardly and register with the down-turned mouths of the bottles as the bottle-containing crates are successively positioned above them, and an additional header 4 is also located preferably above one of the headers 3 to project washing solution downwardly over the exteriors of the inverted bottles. The washing solution for 10 cleansing the interior and exterior of the bottles is supplied from a manifold 5 having branches 6 which lead to the nozzle headers, individual valves 7 being preferably provided in the branches to control the 15 flow of washing solution to the different headers as may be desired. The manifold 5 receives the washing solution through a valve 8 which is preferably of the poppet type, the valve receiving the washing solution 20 from a suitable source of supply, preferably a pump (not shown), the suction side of which is connected to an outlet 9 which leads from the bottom of the washing compartment 2, this arrangement enabling the 25 washing solution to be used repeatedly in the operation of washing the bottles. This valve 8 is opened and closed in correct timed relation to the intervals elapsing between the advancing movements of the bottle-containing 30 crates. The body of the machine also provides a rinsing compartment 10 above which is located a pair of headers 11 which are provided with upturned nozzles for projecting rinsing water into the mouths of the 35 inverted bottles positioned above them, and as shown, an additional rinsing water header 12 is located above one of the headers 11 and is adapted to project rinsing water downwardly over the exteriors of the bottles 40 contained in the crates. The rinsing water headers receive rinsing water from a manifold 13 through branches 14 which lead therefrom to the different headers, and cut-off or controlling valves 15 are preferably 45 provided in these branches to control the supply of rinsing water to the different headers. The rinsing water is supplied to the manifold 13 through a valve 16 which is preferably of the poppet type, and this 50 valve may receive rinsing water from any suitable source of supply, although it is preferable to connect it to the delivery side of a pump (not shown) the inlet of which is connected to an outlet 17 leading from the 55 rinsing compartment 10, this arrangement enabling rinsing water in the compartment 10 to be used repeatedly. The rinsing operation is preferably followed by a sterilizing treatment and, as shown in the present instance, the machine has a sterilizing compartment 18, above which is located a header 19 provided with upturned nozzles adapted to project steam or other appropriate sterilizing medium into the mouths of the 60 inverted bottles. The steam or sterilizing medium is supplied to the header 19 by a valve 20 which is preferably of the poppet type, and this valve is opened and closed in appropriate timed relation to the intervals elapsing between the advancing movements 65 of the bottle-containing crates. In order to attain simplicity in construction and to insure correct timing of the opening and closing of the valves 8, 16 and 20, these valves, according to the present invention, 70 are operated by a common cam shaft 21 which extends longitudinally at one side of the machine and is journaled in suitable bearings 22. This cam shaft has an appropriately shaped cam 23 thereon to cooperate with a roller 24 on the stem of the valve 8, it has an appropriately shaped cam 25 thereon to cooperate with a roller 26 on the stem of the valve 16, and it has an appropriately shaped cam 27 thereon to cooperate 75 with a roller 28 on the stem of the valve 20. This cam shaft is driven in proper timed relation to the crate advancing mechanism as will be hereinafter described. 80

The machine is preferably provided with a crate-receiving table 29 at its left-hand end (Figure 1) and with a crate-delivery table 30 at its opposite or right-hand end, and a pair of rails 31 extends longitudinally through the machine above the nozzle headers, and these rails provide tracks on which the crates are supported during their advance through the machine, and a pair of guides 32 is also provided to engage them laterally while passing through the machine. 90

The present invention provides relatively simple but positively-operating means for advancing a row of bottle-containing crates through the machine periodically or step-by-step, whereby each crate of bottles will be successively positioned correctly in relation to the different headers which perform the washing, rinsing and sterilizing operations thereon. Preferably and as shown in the present instance, this crate-advancing means comprises a pair of reciprocaory bars or members 33 which extend parallel with and are located preferably at the outer sides of the respective crate-supporting tracks 31. 95

In the preferred construction, as shown in detail in Figure 7, each crate-supporting track 31 is secured to the upper side of a longitudinal frame member 34, and the reciprocaory crate-advancing bar or member 33 rests on the longitudinal frame member 34 and is guided between the outer edge of the track 31 and a rib or flange 35 on the frame member. Each reciprocaory bar or member 33 carries a number of crate-engaging dogs 36, these dogs being of a sufficient number to effect the complete advance of a row of crates through the machine from the receiving table 29 to the 100

105

110

120

125

delivery table 30. The bars 33 are connected to reciprocate in unison, by a cross head or transverse connecting member 37, which is arranged toward one end thereof, as shown in Figure 4, and the crate-advancing dogs on the reciprocating members are located directly opposite to one another, so that in operation each crate will be advanced by engagement therewith of a dog on each reciprocating member. Preferably, the dogs are pivotally mounted on the upper sides of the members 33, pivot pins 38, one of which is shown in detail in Figure 7, being preferably used for this purpose, and each dog is provided with a lug or limit stop 39 on its underside which is adapted to come into engagement with the outer side of the respective reciprocating member 33, when the dog is swung into its operative or crate-engaging position, as shown by the full lines in Figure 5, the lug or stop 39 thus limiting the swing of the dog and sustaining the thrust imposed upon the dog, incident to the advance of the crate which it engages.

25 The crate-engaging dogs on each reciprocating member are operatively connected to swing in unison toward either inoperative or operative position, by a bar 40 which operatively engages pivot pins 41 on the different dogs. The members 33 reciprocate in unison through a distance somewhat greater than the width of the bottle-containing crates, and when the limit of motion of these members in one direction is approached, the bars 40 are actuated to swing the dogs into operative or crate-engaging position, and after the movement of the members 33 in an opposite direction to advance the row of crates has been completed, and the return stroke of the members has commenced, the bars 40 are reciprocated in a reverse direction to swing the dogs into an inoperative or retracted position, relatively to the row of crates, in order to permit the dogs to advance along the row of crates and to engage the crates in advance of the crates previously engaged by them. According to the present invention, means is provided for controlling the dogs which insures certainty in their operation. In the preferred construction, the actuation of the dog-controlling bars 40 to swing the dogs into operative or crate-engaging position is effected by a pair of buffers 42 which are located in alignment with the respective bars 40 and against which the ends of these bars abut, when these bars approach the limits of their return movements. Preferably, yielding or spring pressed buffers are employed to minimize shock and to prevent rebound, each buffer in the present instance, comprising a plunger 43 which is housed to reciprocate in a relatively fixed support 44 on the framework of the machine, and a spring 45 acts on the plunger to force it

forward to an extent which is limited by a stop pin 46. By this arrangement, the dog-actuating bars 40 will encounter the spring pressed buffers as the bars approach the limit of their return stroke, and as their movement continues the buffers will be pressed back against the action of their springs until sufficient resistance is developed by the buffers to restore or arrest the movement of the bars 40 while the members 33 continue their movement, in consequence of which the bars 40 will cause the dogs 36 to rotate relatively to the members 33 and to be thus swung from the dotted line positions into the full line positions shown in Figure 5.

30 The next stroke of the members 33 in a reverse direction or toward the left in Figure 5 will bring the dogs 36 against the rear sides of the respective crates, and as the movement of the members 33 continues, the dogs will advance the crates one step. When the members 33 reach the limit of their crate-advancing stroke, the dogs 36 will rest against the rear sides of the crates. The means preferably employed for retracting the dogs so that they will clear the crates during the following return stroke of the members 33, comprises a pair of arms 47 which are operative to engage the forward ends of the dog-actuating bars 40, immediately after the return stroke of the members 33 has commenced, and to push these bars 40 in the same direction in which the members 33 are moving, but at a greater speed, in consequence of which the dogs will be rotated about their pivots, from the dotted line positions to the full line positions shown in Figure 6, and the dogs will remain in the full line position until the end of the return stroke is approached, whereupon the buffers will engage the bars 40 and return the dogs to operative position in the manner previously described. These arms 47 are preferably fixed to a rock shaft 48 which is mounted in suitable bearings 49 in the upper part of the frame of the machine, and one end of the rock shaft is provided with an arm or crank 50 which is operatively connected by a rod or link 51 to a lever 52. This lever is pivoted at 53 to a bracket 54 secured at one side of the machine and carries a roller 55 which cooperates with a cam 56 on the cam shaft 21. Suitable means is provided for holding the roller 55 in engagement with the cam 56, a weight 56^a being fixed to the rock shaft 48 for this purpose, in the instance shown. By this arrangement, the arms 47 will operate in predetermined timed relation with the cycle of operations of the machine, to retract the dogs at the proper times.

35 The crate-advancing bars 33 are reciprocated preferably by a regular motion during the operation of the machine and dif-

- ferent mechanisms may be used for obtaining this result. In the present instance, the cross head 37 which connects the reciprocating bars or members 33, is operatively connected by a link 57 to the upper end of a lever 58, the latter being pivoted at 59 to a relatively fixed bracket 60 on the base of the machine, and this lever is operatively connected to a rod 61, the latter being actuated by a crank pin 62 on a driving gear 63. The latter is mounted on a shaft 64 which is journalled in a suitable bearing on a bearing frame 65, and the gear 63 is driven by a pinion 66 fixed on an intermediate shaft 67, the latter being journalled also in the bearing frame 65. The intermediate shaft 67 has a larger gear 68 fixed thereon which meshes with a pinion 69 fixed on a shaft 70, the latter being journalled in the bearing frame 65, and this shaft 70 has a larger gear 71 fixed thereon and meshing with a pinion 72 on a shaft 73, to receive motion from any suitable source, an electric motor being preferably used, in which case, the shaft 73 may be the electric motor shaft.
- The cam shaft 21 which controls the valves 8, 16 and 20 and also the dog-restoring arms 47 of the crate-advancing mechanism, is driven in definite timed relation with the mechanism just described which actuates the crate-advancing mechanism. Preferably and as shown, the shaft 64 extends through the side of the machine adjacent to the cam shaft and is connected by miter gears 74 to an intermediate shaft 75, the latter being journalled in a bearing 76 and connected by gears 77 to the cam shaft 21, these gears being fixed on the cam shaft and the shaft 75 respectively, and of equal size.
- The mode of operation of a bottle washing, rinsing and sterilizing machine embodying the present invention, as hereinbefore described, is as follows: Assuming that a suitably prepared washing solution is contained in the compartment 2, a suitably prepared rinsing water or liquid is contained in the compartment 10 and that the valve 20 is connected to receive steam or other suitable sterilizing medium, the pumps connected to the valves 8, 16 are set into operation and the motor or other driving shaft 73 is set into operation. Under these conditions, the gear 63 carrying the crank pin 62 will produce a to-and-fro motion of the lever 58 and the latter, through its connection with the reciprocating crate-advancing members 33, will be alternately reciprocated toward the right in Figures 4, 5 and 6, during which stroke the dogs will be in retracted position until the end of each stroke is nearly completed, whereupon the dogs will be swung inwardly to engage behind the row of crates within the machine, as previously described, and on the reverse or left-hand stroke of the members 33, the dogs will

advance the row of crates engaged by them until the lever 58 reaches the end of its stroke, the commencement of the return stroke of the members 33 being accompanied by movement of the arms 47 toward the right in Figures 4 and 6, whereby the dog-controlling bars 40 will act to swing the dogs into inoperative or retracted position, so that they will clear the row of crates during the return stroke of the crate-advancing mechanism. The cam shaft 21 which actuates the arms 47 and also controls the opening and closing of the valves 8, 16 and 20, is driven, through the gearing hereinbefore described, in definite timed relation to the operation of the crate-advancing mechanism, whereby the arms 47 will operate in correct relation to the strokes of the crate-advancing mechanism and also the valves will cause projection of the washing, rinsing and sterilizing mediums into or onto the bottles, while the crates of bottles are at rest and are positioned opposite to the respective headers. As shown, the cam shaft 21 revolves once to each to-and-fro motion of the crate-advancing mechanism, and the cams 23, 25 and 27 are so shaped that the valves 8, 16 and 20 will be closed during the period that the row of crates is being advanced, and these valves will be opened during the intervals that the crates are at rest and the crate-advancing mechanism is making its idle or return stroke.

During the operation of the machine, the crates containing bottles to be washed or cleaned are placed successively on the receiving table 29 where they are picked up successively by the crate-advancing mechanism and automatically conveyed successively to the different operative mechanisms of the machine, and the crates containing the washed, rinsed and sterilized bottles are removed successively from the delivery table 30 to which they are delivered automatically by the crate-advancing mechanism.

Crate-feeding or advancing mechanism constructed in accordance with the present invention possesses the important practical advantages that the crate-engaging dogs are mechanically or positively set in operative and inoperative positions, from which it results that the crates are advanced with certainty and the operation of the mechanism is automatic, requiring no attention from the attendants other than the supplying of the bottles to be washed to the receiving table and removal of the washed bottles from the delivery table. The crate-advancing mechanism is also simple and durable. By providing a cam shaft to operate the fluid-controlling valves and also the dog-resetting arms, and driving this cam shaft from the driving means for the crate-advancing mechanism, a simple and durable construction is obtained which insures the maintenance of

correct timing between the valves, dog-resetting arms and the crate-feeding mechanism.

I claim as my invention:

5. 1. Crate-advancing mechanism for bottle-washing and similar machines comprising, in combination, a reciprocatory member carrying a dog movable relatively to it, means for moving the dog relatively to said member to set it in operative crate-engaging position when said member is near one end of its stroke, and means for resetting said dog in inoperative position when said member is near the other end of its stroke. 70
15. 2. Crate-advancing mechanism for bottle-washing and similar machines comprising, in combination, a reciprocatory member carrying a dog capable of being set in operative crate-engaging position and reset in 75
20. non-engaging position, means for positively setting said dog in operative crate-engaging position while said member is toward one end of its stroke, and means for positively resetting said dog in inoperative non-engaging 80
25. position while said member is toward the other end of its stroke. 85
3. Crate-advancing mechanism for bottle-washing and similar machines comprising, in combination, a reciprocatory member carrying a dog capable of being set and of remaining in either an operative crate-engaging position or an inoperative non-engaging position, means for mechanically setting the dog in operative position while said member is toward one end of its stroke, and means for mechanically setting the dog in inoperative position while said member is toward the other end of its stroke. 90
4. Crate advancing mechanism for bottle-washing and similar machines comprising, in combination, a reciprocatory member carrying a movable dog capable of being set in operative and inoperative position relatively to a crate to be advanced, operating 95
45. means connected to said member for reciprocating it, and controlling means operative in consequence of the movement of said member in one direction to set said dog in operative position. 100
50. 5. Crate-advancing mechanism for bottle-washing and similar machines comprising, in combination, a reciprocatory member carrying a dog movable relatively to it into operative crate-engaging position and inoperative non-engaging position, and a stationary abutment operative in consequence of the movement of said member in one direction to act on said dog to set it in one of said positions. 105
55. 6. Crate-advancing mechanism for bottle-washing and similar machines comprising, in combination, a reciprocatory member carrying a dog movable relatively to it and capable of being set in operative crate-engaging position and in inoperative non-en- 110
65. gaging position, and means including a buffer for yieldingly acting, during the final part of the movement of said member in one direction, to set said dog in one of said positions. 115
7. Crate-advancing mechanism for bottle-washing and similar machines comprising, in combination, a reciprocatory member carrying a series of pivotal longitudinally-spaced dogs, operating means connected to said member for reciprocating it, a bar connecting said dogs and movable with and also relatively to said member to concurrently set the series of dogs either in operative crate-engaging position or in inoperative non-engaging position, and means arranged to act on said bar, while said member is approaching one end of its stroke, to set the dogs in one of said positions. 120
8. Crate-advancing mechanism for bottle-washing and similar machines comprising, in combination, a reciprocatory member carrying a plurality of pivoted longitudinally-spaced dogs, a bar operatively connected to said dogs and movable in unison with said member and also shiftable end-wise relatively to said member to set said dogs in operative crate-engaging position and in inoperative non-engaging position, and means including a buffer arranged to act on one end of said bar, in consequence of the movement of said member in one direction, to shift said bar relatively to said member and thus set the dogs in one of said positions. 125
9. Crate-advancing mechanism for bottle-washing and similar machines comprising, in combination, a reciprocatory member carrying a plurality of pivoted crate-advancing dogs, a bar operatively connected to said dogs and movable in unison with said member and also shiftable relatively to said member to set said dogs in operative and inoperative positions, and a spring buffer arranged in the path of one end of said bar and operative thereon, in consequence of movement of said member in one direction, to relatively shift said bar and thus set the dogs in one of said positions. 130
10. Crate-advancing mechanism for bottle-washing and similar machines comprising, in combination, a reciprocatory member carrying a plurality of longitudinally spaced dogs capable of movement relatively to said member to set them in operative and inoperative positions, means operative on one end of said bar while said member is toward one end of its stroke to shift it relatively to said member and thus set the dogs in operative position, and means operative on the opposite end of said bar while said member is toward the other end of its stroke to reverse the position of the bar relatively to said member and thus set the dogs in inoperative position. 135
11. Crate-advancing mechanism for bot-

- tle-washing and similar machines comprising, in combination, a reciprocatory member carrying a dog capable of being set in operative crate-engaging position and in inoperative 5 non-engaging position, means for setting the dog in one of said positions during the final part of the stroke of said member in one direction, and means operative to reverse the position of the dog during the commencement 10 of the stroke of said member in the other direction.
12. Crate-advancing mechanism for bottle-washing and similar machines comprising, in combination, a reciprocatory member carrying a dog capable of being set in operative and inoperative positions, means for setting said dog in one of said positions while said member is toward one end of its stroke, and an arm operative during and at a speed 15 greater than that of the stroke of said member in the opposite direction to set the dog in the other of said positions.
13. Crate-advancing mechanism for bottle-washing and similar machines comprising, in combination, a reciprocatory member carrying a plurality of longitudinally-spaced crate-feeding dogs, a bar operatively connected to said dogs and movable in unison with and also relatively to said member, means for causing movement of said bar in one direction to set the dogs in operative 20 position preparatory to a stroke of said member in one direction, and means operative on the opposite end of said bar during the commencement 25 of the stroke of said member in the opposite direction to shift said bar at a speed greater than that of said member and thereby reverse the position of the dogs.
14. Crate-advancing mechanism for bottle-washing and similar machines comprising, in combination, a reciprocatory member carrying a plurality of crate-feeding dogs, a bar extending longitudinally of said member and movable in unison with and also relatively to said member, said bar being operatively connected to said dogs, and means for shifting the bar relatively to said member in the direction in which said member is moving but at a greater speed during the stroke of said member in one direction.
15. Crate-advancing means for bottle-washing and similar machines comprising, in combination, a pair of reciprocatory members connected to operate in unison and carrying pivoted crate-feeding dogs, actuating bars extending longitudinally of the respective members and operatively connected to the dogs thereon, means for reciprocating 55 said members, means operative on said bars toward one end of the stroke of said members to shift them relatively to said members and thereby set the dogs in operative crate-engaging position, and means 60 operative on said bars toward the other end of the stroke of said members to shift them relatively to said members in a reverse direction and thereby set the dogs in inoperative position.
16. Crate-advancing mechanism for bottle-washing and similar machines comprising, in combination, a pair of reciprocatory members connected to operate in unison and carrying crate-feeding dogs, actuating bars 65 extending longitudinally of said members and operatively connected to the dogs on the respective members, means for reciprocating said members, and means for setting said dogs embodying a pair of arms connected to swing in unison in the direction of movement of said members, and means for advancing said arms, during a stroke of said members in one direction, in the same direction but at a greater speed than that of said members.
17. Crate-advancing mechanism for bottle-washing and similar machines comprising, in combination, reciprocatory members carrying crate-feeding dogs, driving means for regularly reciprocating said members, means for setting said dogs relatively to the crates to be advanced, and means including a cam shaft and cam thereon driven in definite timed relation with said driving means for periodically actuating said dog setting means.
18. Crate-advancing mechanism for machines of the class described comprising in combination, a pair of supports, parallel crate-supporting rails on the upper side 100 thereof, a member guided to reciprocate longitudinally on the upper side of each support alongside of the respective rail, crate-feeding dogs pivoted on the upper sides of said members and movable to and from positions overlying said rails, and means for setting said dogs.
19. In crate-advancing mechanism for machines of the class described, the combination of a support, a crate-supporting rail 110 extending longitudinally thereof, a member guided to reciprocate longitudinally on the upper side of said support and along one side of said rail, a crate-feeding dog pivoted on the upper side of said member and adapted to swing to and from a position overlying said rail, means for setting the dog, and a stop on the underside of the dog to cooperate with a side of said member to limit the swing of the dog and sustain the thrust 115 imposed upon it incident to the advance of a crate thereby.
